 N. J., a corporation of New Jersey

Application September 2, 1933, Serial No. 688,039

1 Claim. (Cl. 171—229)

This invention relates to voltage regulators for dynamo electric machines, and particularly for generators driven from engines of variable speed, and operating to supply a variable or constant current demand.

An object of the invention is to provide in a regulating system including a rheostat, novel means for actuating the rheostat to vary the strength of the generator field immediately upon the occurrence of a rise or fall in line voltage, and then hold the new setting steadily, and without the period of fluctuation which characterizes certain conventional regulators now used.

In the preferred embodiment, shown schematically in the accompanying drawing, the rheostat is operated by differential gearing driven in one direction or the other, as required, by electro-magnetic means, the movement in either direction being stopped instantly, as soon as the normal voltage is restored. It is to be understood, however, that the maintenance of the electrical connections precisely as shown is not essential, the drawing being illustrative rather than definitive of the scope of the invention.

25 In the drawing.

Fig. 1 is a diagrammatical view of the invention as applied to the variable speed generator;

Fig. 2 is a view in elevation showing the rheostat actuating mechanism; and

30 Fig. 3 is another view of the rheostat actuating mechanism as seen at right angles to the view point of Fig. 2.

In the drawing, reference character G designates a generator armature rotatable through suitable mechanical connections (not shown) leading to an internal combustion engine crank-shaft or other prime mover. The shunt field winding 6 of the generator is shown as connected in series with the coil 7 of a rheostat, the movable arm 8 of which is electrically connected to one brush 9 of the generator, through interposed leads 11 and 12. The arm 8 is also shown as mechanically secured to a rock-shaft 13 which terminates in a cage carrying a pair of bevel gears 14 and 15 (Fig. 2) constituting elements of a differential planetary gear set which includes additional bevel gears 16 and 17, the latter two being in constant mesh with the other two and mounted for rotation on separate, but aligned, shafts 18 and 19 respectively, the said shafts being capable of independent step by step rotation in response to electrical impulses created by the means now to be described. By way of example the differential gear set is shown as of the type disclosed in

on March 1st, 1927; the specific construction used is not claimed except generically, as an element of the combination comprising the regulating system.

The means for actuating a selected one of the shafts 18, 19, while preventing actuation of the one not selected, preferably includes a pair of electro-magnets having windings 21 and 22, respectively, surrounding cores whose ends cooperate with armatures 23 and 24, respectively, to cause relatively rapid oscillation thereof as current is passed through the associated winding at regularly recurring intervals of relatively high frequency. In order to transmit these oscillations to the shaft 18 or the shaft 19 (depending upon which electro-magnet is energized) the former is provided with a ratchet wheel 27 rotatable step by step in a clockwise direction, as viewed from the left in Fig. 2, and the latter with a similar ratchet wheel 28 rotatable step by step in a clockwise direction, the rotation in one case being produced by means of a pawl 31 pivotally connected to one end of the armature 23, and the other armature 24 being provided with a similar pawl 32 having engagement with the teeth of ratchet 28.

The means for selecting the proper electro-magnet for energization is shown in Fig. 1 as constituted by a third electro-magnet 33 having an armature 34 adapted to occupy any one of three positions, depending upon the strength of the magnetic attraction thereupon, which in turn depends upon the voltage impressed upon the winding 33, said voltage being the generator voltage by reason of the fact that the winding 33 is connected directly across the line, as by leads 37 and 38. When the voltage is sub-normal, the armature engages fixed contact 39; when abnormal, it engages fixed contact 40; and when normal, it remains between said contact, but out of engagement therewith; a suitable centering spring 41 or other means being provided to prevent movement of the armature so long as the deviation from normal remains negligible. A second spring 45 is provided to draw the armature 34 downward under sub-normal voltage conditions. Lead 42 connects contact 39 with electro-magnet 21, and lead 43 connects contact 40 with electro-magnet 22. Both magnets 21 and 22 have a common connection 44 with the terminal 46 of a commutator or circuit interrupter 47, the other terminal of which connects with the positive side of the main generator line, as shown at 48. This device 47 is driven through suitable reduction mechanism (not shown) from the generator

shaft 48, and includes a disk having a non-conducting portion 51 adapted to interrupt the flow of current once each revolution; hence the frequency of energization of the windings 21, 22 will be governed by the speed of this circuit interrupting commutator 47. Preferably this speed will be approximately one-fourth that of generator armature.

From the foregoing it is apparent that the 10 operation is as follows:

Upon an increase in voltage the coil 33 overcomes spring 45 and causes armature 34 to engage contact 40 to energize coil 22 in the circuit including conductors 48 and 44. Each time this 15 circuit is broken at 41, pawl 32 and ratchet 28 operate through differential 13 to move arm 8 so as to decrease the flow of current through field 6 by increasing resistance 7 in series with field 6. If the voltage decreases below the predetermined 20 normal value contacts 39, solenoid 21 and ratchet mechanism 31, 27 operate through gears 16 and 14 to increase the voltage.

Upon starting the generator, the entire field 25 resistance may be cut out of circuit by providing

a shunt switch 52 which opens when the generator reaches approximately 80% of the desired voltage, the switch being opened by means of a solenoid 53 connected across the line. The balancing, or centering spring 41 serves not only as 5 a deterrent to excessive vibration of the armature 34, but also as a means of compensating for the variable magnetic pull upon the armature as the air gap between armature and core increases and decreases.

10

What is claimed is:

In combination with a rheostat having a movable resistance varying element, means for moving said element comprising an actuating shaft, reciprocable means responsive to a voltage drop 15 for rotating said shaft in one direction, additional reciprocable means responsive to a voltage rise for rotating said shaft in the reverse direction, and a differential gear train connecting said reciprocable means with said actuating shaft, said 20 gear train having one element thereof locked against rotation by one of said reciprocable means while the remaining elements of the gear train are being rotated.
